UNITED STATES PATENT OFFICE.

CHARLES L. CORCORAN, OF NORTHFIELD, NEW JERSEY.

TRAVELING ROCKING-HORSE.

936,092.

Specification of Letters Patent.

Patented Oct. 5, 1909.

Application filed June 23, 1903. Serial No. 440,045.

To all whom it may concern:

Be it known that I, CHARLES L. CORCORAN, citizen of the United States, residing at Northfield, in the county of Atlantic and State of New Jersey, have invented certain new and useful Improvements in Traveling Rocking-Horses, of which the following is a specification.

The present invention has relation to amusement devices, being designed most especially to provide a rocking object mounted upon wheels and interposing connections between a set of wheels and the oscillating object to utilize the teetering motion as propelling means for advancing or causing the device as a whole to travel.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a side view of a device embodying the invention, the teetering movement of the figure being shown by full and dotted lines. Fig. 2 is a horizontal section on the line $x-x$ of Fig. 1. Fig. 3 is a detail perspective view of the steering and power translating devices. Fig. 4 is a detail view of a part of the steering device, showing a portion of the figure and the standards. Fig. 5 is a detail view, showing the means for connecting the pitman to the figure.

Corresponding and like parts are referred to in the following description and indicated in all the views of the drawings by the same reference characters.

The device embodies a platform 1 mounted upon wheels 2 and 3, the latter being secured to an axle 4 and the former loose upon an axle 5 which is mounted to turn about a king bolt or vertical axis 6, a fifth wheel 7 being provided to give stability to the fore-truck embodying the said axle 5 and wheels 2. Standards 8 rise from the platform 1 and are strengthened by braces 9. The teetering object 10 is mounted upon the standards 8 so as to receive an oscillatory movement. The object 10 may represent a horse or other ani-

mal, or may consist of a car, or any type of structure adapted to receive an oscillatory movement by the weight of the person mounted thereon.

For utilizing the oscillating movements of the object 10, the following means are employed: A shaft 11 is journaled in bearings of the platform 1 and is provided with a crank 12 and a gear wheel 13, the latter meshing with a pinion 14 fast to the axle 4. A pitman or rod 15 connects the crank 12 with the object 10, the upper end of said pitman being adapted to be adjustably connected with said object at 16 to admit of varying the teetering movements of the object. It will be understood that as the object or figure 10 is oscillated by the rider, the movement is transmitted by the pitman 15 to the shaft 11 and from the latter to the axle 4, thereby causing the device to travel.

For steering the device a cross bar 17 is provided and in the present instance represents a bit mounted in the mouth of the animal so as to be turned, lines 18 extending from opposite ends of the cross bar or bit and under control of the rider. A shaft 19 mounted in the head of the figure is provided at opposite ends with gear wheels 20 and 21. The gear wheel 20 is in mesh with a toothed segment or mutilated gear 22 fast to or forming a part of the cross bar 17. The gear wheel 21 is in mesh with a gear wheel 23 fast to the upper end of a shaft 24 which is mounted in the body of the figure and inclines rearwardly and downwardly from the end gear of the shaft 19. A vertical shaft 25 mounted in bearings connecting the standards 8 is coupled at its upper end by means of a universal joint 26 to the lower rear end of the shaft 24. A longitudinal shaft 27 mounted in bearings of the platform is provided at opposite ends with gear wheels 28 and 29, the latter meshing with a gear wheel 30 fast to the lower end of the vertical shaft 25. The gear wheel 28 meshes with a gear wheel 31 fast to the upper end of the king bolt or like part 6 fast at its lower end to the fore-truck so as to turn the same to properly direct the device in its movements.

The rider mounted upon the teetering object or figure imparts an oscillating movement thereto by either shifting the weight forward and backward, or by swaying the body fore and aft. The teetering movement of the object 10 is converted into a ro

tary movement by means of the pitman 15 and crank 12 and is transmitted to the rear axle by means of the gearing 13 and 14, thereby causing the object to move or travel.

6 To steer the device one of the lines 18 is pulled upon, thereby causing the cross bar 17 to turn, said movement being transmitted to the fore-truck by means of the connections set forth, with the result that the device 10 may be directed in a straight course, or caused to move either to the right or to the left, as may be desired.

To prevent the object stopping upon a dead center and to positively apply the force 15 for propelling the device, it is proposed to add a shaft 32 to the platform near its front end, said shaft having a crank portion 33 which is connected by pitman 34 to the object in a manner similar to the pitman 15.

20 A gear wheel 36 fast to the shaft 32 meshes with a pinion 37 fast to the front end of a longitudinal shaft 38, said shaft having a pinion 39 at its rear end in mesh with a gear wheel 40 fast to the axle 4. By proper 25 adjustment of the parts, a dead center is prevented, and each down movement of the figure or object is positively utilized for propelling the device, thereby enabling the combined weight of the rider and object to be 30 advantageously utilized in propelling the device, as will be readily understood.

Having thus described the invention, what is claimed as new is:

1. In combination, a platform, front and 35 rear sets of wheels supporting the platform, a pivotally mounted axle supporting one of the sets of wheels, a teetering object mounted upon the platform, means for transmitting power from the teetering object to the wheels 40 for propelling the device, a cross bar pivoted upon the object and under control of the rider, a series of connected shafts mounted upon the platform and geared at one end to the said pivoted axle and terminating at the 45 opposite end about in line with the axis of the teetering object, and a second series of connected shafts mounted upon the teetering object and geared at one end to the said cross bar and at the opposite end to the first set of 50 connected shafts.

2. In combination, a platform, front and

rear sets of wheels carried by said platform for supporting the same, one of said sets of wheels arranged to turn for steering the platform, a teetering object mounted upon the platform and connected with the other set of wheels for propelling the device; shafts carried, one by said teetering object, and the other by said platform and connected to each other by a universal joint, a 60 shaft geared between one of said shafts and the turning set of wheels, and a cross-bar connected to the other of said shafts to turn the same under the control of a rider mounted on said teetering object for the purpose of 65 guiding the platform.

3. In combination, a platform, front and rear axles provided with wheels and attached to the platform for supporting the same, the front axle being pivoted, standards projected 70 upward from the platform, a teetering object mounted upon the standards, a longitudinal shaft 27 geared at one end to the front axle, a vertical shaft 25 mounted in said standards and geared to the longitudinal 75 shaft 27, an inclined shaft 24 mounted upon the teetering object and connected with the shaft 25 by means of a universal joint, a shaft 19 inclined in an opposite direction to the shaft 24 and geared thereto, and a cross 80 bar 17 geared to the shaft 19 said cross bar being under control of the rider to admit of properly steering the device when in motion.

4. In combination, a platform, front and rear axles attached to the platform and provided with supporting wheels, front and rear crank shafts, gearing between the rear crank shaft and the rear axle, power transmitting means between the front crank shaft and said rear axle, a teetering object mounted upon the platform and connecting means between the teetering object and the crank portions of said shafts, said connecting means having adjustable connection with the teetering object both in front and in the rear 95 of its fulcrum.

In testimony whereof I affix my signature in presence of two witnesses.

CHARLES L. CORCORAN. [L. S.]
